UNITED STATES PATENT OFFICE.

HUGO HORN, OF MILWAUKEE, WISCONSIN.

SPARK-PLUG.

1,290,559.

Specification of Letters Patent.

Patented Jan. 7, 1919.

Application filed June 1, 1918. Serial No. 237,681.

To all whom it may concern:

Be it known that I, HUGO HORN, a citizen of the United States, and resident of Milwaukee, in the county of Milwaukee and 5 State of Wisconsin, have invented new and useful Improvements in Spark-Plugs, of which the following is a description, reference being had to the accompanying drawings, which are a part of this specification.

10 This invention relates to improvements in spark plugs.

It is one of the objects of the present invention to provide a spark plug having a visible spark to indicate that the electrodes 15 of the spark plug within the combustion engine are properly performing their function.

15 A further object of the invention is to provide a spark plug particularly adapted 20 for use in a plural cylinder engine to indicate, in case of trouble, the particular spark plug which is not properly igniting the charge of gas within the cylinder in which the spark plug is mounted.

25 A further object of the invention is to provide a spark plug having means for conveniently adjusting the resistance of the visible or auxiliary air gap to control the strength of the spark igniting the charge 30 within the engine cylinder without removing the plug from the cylinder.

35 A further object of the invention is to provide a spark plug which is of simple construction, is strong and durable and is well adapted for the purpose described.

With the above and other objects in view 40 the invention consists of the improved spark plug and its parts and combinations as set forth in the claims, and all equivalents thereof.

In the accompanying drawing in which the same reference characters indicate the same parts in all of the views;

45 Figure 1 is a side view of the improved spark plug shown on a large scale for convenience of illustration;

Fig. 2 is a vertical sectional view thereof; and

50 Fig. 3 is a transverse sectional view taken on line 3—3 of Fig. 2.

Referring to the drawing the numeral 5 indicates the plug socket or sleeve which is formed with a threaded lower part 6 of any standard size and an enlarged upper part 7 55 having hexagonal faces 8 which are engaged by a wrench in threading the plug into an

engine cylinder. The said upper part 7 has a bore of larger diameter than the lower part which forms an annular tapered shoulder 9 against which bears the medial annular 60 tapered shoulder 10 of the insulating plug 11. The plug may be formed of porcelain, mica or other desirable insulating and heat resisting material and is formed with a lower portion 12, a medial enlargement 13, an upper 65 shouldered part 14, and an upper extension 15 of less diameter than the shouldered portion 14. The tapered shoulder 10 is approximately of the same angle as the shoulder 9 and a copper gasket 10' interposed 70 between the two shoulders forms a gas-tight joint therebetween.

A sight bushing 16 surrounding the insulating plug and threaded into the upper portion of the plug socket impinges against the 75 upper surface of the medial enlargement of the insulating plug and firmly clamps it in the socket and against the gasket. The bushing is formed with eight openings 17 in its opposite sides and these openings are protected by a transparent tube 18, preferably glass, which is positioned within the bushing, and surrounds the insulating plug and is interposed between the upper wall of the bushing and the medial enlargement and 80 forms a spark chamber. A rubber gasket 19' interposed between the bushing and the upper edge of the glass tube holds said tube firmly in position and also permits the unequal expansion of the glass tube and adjacent parts without liability of breaking the parts.

85 A main electrode 20 formed of any desirable metal extends centrally longitudinally through the insulating plug member 11 and projects slightly from the lower end portion thereof. The upper end of the central electrode threads into a threaded extension 21 which projects upwardly from the upper end portion of the insulating plug and has a holding nut 22 and a terminal clamping nut 23 threaded thereon.

90 The insulating plug 11 is also provided with an auxiliary electrode 24 which extends through one side portion of the insulating plug 11 in a line approximately parallel to the central electrode. The lower end portion 24' of the auxiliary electrode is bent 95 toward the lower end portion of the central electrode and terminates a slight distance therefrom to form a spark gap which is jumped by the current to ignite the com- 100 105 110

bustible charge of the engine to which it is connected.

The upper end portion of the auxiliary electrode extends adjacent the upper surface 5 of the shoulder part 14 of the insulating plug and is provided with an enlargement or head 25 which projects above said shoulder and is visible through the sight openings 17.

- 10 An auxiliary sleeve 26 surrounding the insulating plug and threaded through the upper portion of the sight bushing 16 has its lower or inner annular edge portion 26' positioned adjacent the upper end portion 15 of the enlargement or head 25 of the auxiliary electrode 24 to form an auxiliary or ground spark gap which intensifies the spark at the main gap between the electrodes 20 and 24. The sleeve 26 is formed with 20 a milled annular flange 26' for convenience in adjusting the distance between the electrodes forming the ground spark gap. An extension and protecting sleeve 27 surrounds the upper end portion of the insulating plug 25 and is interposed between the sleeve 26 and the nut 22.

In use the spark plug is mounted on an engine and connected to the ignition electric circuit in the usual manner and when operating in proper manner the auxiliary spark 30 is visible through the sight openings of the sight bushing thus enabling the user to easily determine if any of the cylinders of the engine miss firing. The auxiliary spark gap 35 also intensifies the spark of the main gap, which tends to increase the efficiency of the combustible charge and also tends to prevent carbon deposits forming on the electrodes at the spark gaps.

- 40 From the foregoing description it will be seen that the spark plug is of very simple construction and is well adapted for the purpose described.

What I claim as my invention is:

- 45 1. A spark plug, comprising a plug socket having a threaded lower part, a sight bushing threaded on the plug socket, an insulating plug member extending into the plug socket and through the sight bushing, a 50 main electrode extending through the insulating plug, an auxiliary electrode extending through a portion of the insulating plug and having its lower end terminating adjacent the lower end portion of the main electrode 55 to form a main spark gap therebetween, and a sleeve threaded into the bushing and extending adjacent the upper end portion of the auxiliary electrode to form an auxiliary spark gap and ground connection there- 60 between.

2. A spark plug, comprising a plug socket having a threaded lower part and an enlarged upper part forming an inner shoulder, an insulating plug member extending 65 into the plug socket and having a medial en-

largement which bears against the inner shoulder, a bushing threaded into the enlarged upper part of the plug socket and bearing against the enlargement of the insulating plug, said bushing having a sight 70 opening, a main electrode extending longitudinally through the insulating plug, an auxiliary electrode extending through a portion of the insulating plug and having its lower end terminating adjacent the lower 75 end portion of the main electrode to form a main spark gap therebetween, an electrode sleeve threaded into the bushing and extending adjacent the upper end portion of the auxiliary electrode to form an auxiliary 80 spark gap and ground connection therebetween which is visible through the sight opening, and a terminal connection means at the upper end of the main electrode.

3. A spark plug, comprising a plug socket 85 having a threaded lower part and an enlarged upper part forming an inner shoulder, an insulating plug member extending into the plug socket and having a medial enlargement which bears against the inner 90 shoulder, a bushing threaded into the enlarged upper part of the plug socket and bearing against the enlargement of the insulating plug, said bushing having a sight 95 opening, a main electrode extending longitudinally through the insulating plug, an auxiliary electrode extending through a portion of the insulating plug and having its lower end terminating adjacent the lower end portion of the main electrode to form a 100 main spark gap therebetween, an electrode sleeve threaded into the bushing and extending adjacent the upper end portion of the auxiliary electrode to form an auxiliary 105 spark gap and ground connection therebetween which is visible through the sight opening, an extension sleeve surrounding the upper portion of the insulating plug member and bearing against the electrode sleeve, a nut threaded on the main electrode 110 and bearing against the extension sleeve, and a terminal connection means at the upper end of the main electrode.

4. A spark plug, comprising a metal plug socket having a spark chamber in its upper 115 end portion, an insulating member extending through the spark chamber, a main electrode extending through the insulating member, an auxiliary electrode extending through a portion of the insulating member and having one of its end portions terminating adjacent the lower end of the main electrode 120 and its other end terminating within the spark chamber, and a sleeve adjustably mounted on the spark plug and extending 125 into the spark chamber to a position adjacent the end of the auxiliary electrode within said chamber to form an auxiliary and ground spark gap therebetween.

5. A spark plug, comprising a metal plug 130

socket having a threaded lower end portion and a spark chamber in its upper end portion, an insulating member extending through the threaded portion and the spark 5 chamber, a main electrode extending through the insulating member, an auxiliary electrode extending through a portion of the insulating member and having one of its end portions terminating adjacent the lower end 10 of the main electrode and its other end terminating within the spark chamber, said spark chamber formed in part of a bushing having a sight opening, a sleeve surrounding the insulating member and threaded into the 15 bushing and having its inner edge portion positioned adjacent the end of the auxiliary electrode within the chamber to form an auxiliary and ground spark gap therebetween, and a terminal connection means 20 on the upper end portion of the main electrode.

6. A spark plug, comprising a plug socket having a threaded lower part and an enlarged upper part provided with an internal 25 thread, said enlargement forming an inner shoulder, an insulating plug member extending into the plug socket and having a medial enlargement which bears against the socket shoulder, said insulating plug also 30 having a shouldered portion, a bushing threaded into the plug socket and bearing

against the enlargement of the insulating plug member and having opposite sight openings, a transparent tube positioned within the bushing and surrounding the 35 insulating plug member and bearing against the enlargement of the insulating plug member, and in part forming a spark chamber; a main electrode extending longitudinally through the insulating plug member, an auxiliary 40 electrode extending through a portion of the insulating plug member and having its lower end bent at an angle and terminating adjacent the main electrode to form a main spark gap therebetween, the upper 45 end of the auxiliary electrode having an enlargement which terminates in the spark chamber, an electrode sleeve threaded into the plug member and surrounding the insulating plug member and having its inner 50 edge portion positioned adjacent the end of the auxiliary electrode within the chamber to form an adjustable auxiliary and ground spark gap therebetween, an extension sleeve bearing against the sleeve electrode, a nut 55 threaded on the upper end of the main electrode and bearing against the extension sleeve, and a terminal nut threaded on the upper end of the main electrode.

In testimony whereof, I affix my signature. 60

HUGO HORN.
